UNITED STATES PATENT OFFICE

ISAAC A. BAUM, OF CHICAGO, ILLINOIS

FRAMED WALL OPENING

Application filed July 22, 1929. Serial No. 380,208.

My invention relates to buildings and particularly to a novel form of connection between a masonry wall and a steel frame for a wall opening.

It is customary and, in fact, the universal practice, where steel frames are inserted in wall openings, to construct the wall of masonry or other element with the thickness of the wall corresponding substantially to the thickness of the buck or jamb and then finishing the wall interior and exterior, or both, with plaster or other materials.

It is also becoming an accepted practice to build the wall of masonry elements such as tile without interior or exterior finish; in other words, to allow the side faces of the tile to constitute the exposed surfaces of the walls. In the use of metal buck or jamb members this presents objections due to the difficulty in decorating or otherwise harmonizing the relatively large exposed area of metal.

I have devised a wall construction in which the masonry elements are of the full thickness of the finished wall and with the edge bounding the wall opening of reduced thickness, thus permitting a channel-shaped buck to be fitted thereover. The open space resulting from such association of elements is filled with plaster or other plastic material in a desired manner.

The invention will be more readily understood by reference to the accompanying drawings, in which

Fig. 1 is a perspective sectional view of a fragment of a wall arranged in accordance with my invention; and

Fig. 2 is a sectional view, therethrough.

In the drawings, I have illustrated a masonry wall consisting of tiles 10, one or both of the faces of which may be finished to provide an attractive inner or outer exposure. At the edge bounding the wall opening, the tiles are of reduced thickness thus providing the portion 11. Preferably the abutment or edge at the junction of the reduced portion with the main portion is undercut as at 12, and if desired for decorative purposes, the flange 13 resulting from the undercutting is notched or scalloped, as at 14.

The door frame is of a form illustrated in several of my copending applications for patents, comprising a jamb 15, door stop 16, and side flanges 17 resulting in a channel shaped member that snugly fits over the reduced portion 11. Preferably the flanges 17 are provided with struck out loops or projections 18 that serve as anchors for the plaster. A plaster finish member in the form of a continuous L-shaped strip 19 is welded to the outer faces of the flanges 17, the strips having a rebent margin 20 that acts also to anchor the plastic material indicated at 21.

The provision of the undercut abutment 12 serves to securely anchor the plaster to the masonry and the other anchors already referred to serve the same purpose with relation to the frame. Thus the surfaces of the wall is continued to the edge of the finish member 19.

If desired, as indicated in Fig. 2, I may provide a molding strip 22 of wood or stone on the inside face of the wall.

Obviously, the exact form and arrangement is not essential and modifications may be made in the construction without departing from the spirit of my invention.

I claim:

1. In wall construction, the combination of a metal jamb and buck of generally channel shape and masonry elements having a thickness substantially equal to the thickness of the finished wall and being of reduced thickness at the point of the door opening, said channel fitting over the portion of reduced thickness, and a plaster finishing member projecting from the side of the channel and terminating substantially in the plane of the exterior surface of said masonry element.

2. In wall construction, the combination of a metal jamb and buck of generally channel shape and masonry elements having a thickness substantially equal to the thickness of the finished wall and being of reduced thickness at the point of the door opening, said channel fitting over the portion of reduced thickness, a plaster finishing member projecting from the side of the channel and terminating substantially in the plane of the

exterior surface of said masonry element, and plastic material in the space between the finish member and the edge of the masonry element.

- 5 3. In wall construction the combination of a jamb and buck of generally channel shape provided with a continuous plaster finish flange projecting laterally from a side flange of the channel, a masonry element having 10 an end portion of reduced thickness with the channel fitting over the said reduced portion thereby leaving an open space between the plaster finish member and the edge formed by the reduction in thickness of the 15 masonry element, and plaster in said space.
4. In wall construction the combination of a jamb and buck of generally channel shape provided with a continuous plaster finish flange projecting laterally from a side flange 20 of the channel, a masonry element having an end portion of reduced thickness with the channel fitting over the said reduced portion thereby leaving an open space between the plaster finish member and the edge formed 25 by the reduction in thickness of the masonry element, plaster in said space, and means for anchoring the plaster in said space.

5. In combination a metal frame member of channel shape in cross section having a 30 continuous lateral flange acting as a plaster terminal and ground, a masonry element of reduced thickness at its edge over which said frame member is snugly fitted, the abutment formed by reducing the thickness of said 35 masonry element being undercut, and plaster in the space between said plaster terminal and said undercut abutment.

6. In wall construction, the combination of a plurality of masonry elements having portions of reduced thickness at the edge that outlines a wall opening, a metal frame member having portions fitting over said portions of reduced thickness, and plastic material overlying the part of the frame member that engages the reduced portion.

7. In wall construction, the combination of a plurality of masonry elements having portions of reduced thickness at the edge that outlines a wall opening, a metal frame member having portions fitting over said portions of reduced thickness, plastic material overlying the part of the frame member that engages the reduced portion, and means for anchoring the plastic material to the metal of the frame.

ISAAC A. BAUM.
